UNITED STATES PATENT OFFICE.

ALEXANDER F. MACDONALD, OF SCHENECTADY, NEW YORK, ASSIGNOR TO GENERAL ELECTRIC COMPANY, A CORPORATION OF NEW YORK.

PUMP FOR INTERNAL-COMBUSTION ENGINES.

1,128,023.

Specification of Letters Patent.

Patented Feb. 9, 1915.

Application filed November 9, 1912. Serial No. 730,324.

To all whom it may concern:

Be it known that I, ALEXANDER F. MACDONALD, a citizen of the United States, residing at Schenectady, county of Schenectady, State of New York, have invented certain new and useful Improvements in Pumps for Internal-Combustion Engines, of which the following is a specification.

The present invention relates to fuel pumps for internal combustion engines and especially to the means for controlling the delivery thereof and has for its object to improve the construction and operation of the same.

My invention is intended more especially for use with high compression engines operating on the constant pressure plan. That is to say engines wherein relatively pure air is compressed to a temperature above the igniting temperature of the fuel which is injected at or about the outer dead center by a blast of air or other gas, the introduction being by a pulverizer, injector, or atomizer, subject to the control of a needle valve. The pump is arranged to deliver fuel, such as a crude oil, to the pulverizer against the high blast pressure during the period that the needle valve is closed, and subsequently when the valve is opened the blast pressure discharges the fuel into the combustion space of the engine. In such an engine fuel has to be delivered thereto in measured quantities in accordance with the load requirements. In practice this has been accomplished by controlling the action of the suction valve of the pump by changing the position of the fulcrum of a lever that is vibrated by and in synchronism with the pump plunger, said fulcrum being supported solely by a rod leading to the speed governor. Such an arrangement directly imposes an intermittent load more or less great on the governor, first in one direction and then in another which frequently causes it to "hunt" unless made large and powerful. I aim to improve the governing effect by a novel arrangement of parts as will appear hereinafter.

For a consideration of what I believe to be novel and my invention, attention is directed to the accompanying description and claims appended thereto.

In the accompanying drawing which illustrates embodiments of my invention, Figure 1 is a view partly in elevation and partly

in section of my improved pump governing mechanism; Fig. 2 is a diagram illustrating the action of the mechanism; Fig. 3 is a detailed view of a slight modification, and Figs. 4 and 5 are modifications showing means for changing the timing of the suction valves.

4 indicates a shaft, such for example as the cam shaft of an internal combustion engine. Keyed to the shaft is an eccentric 5 and surrounding it is an eccentric strap 6 that is connected to a sliding cross-head 7, the latter being guided by the guides 8. Connected to the cross-head is a reciprocating pump plunger 9. The lower end of the plunger enters a cylinder 10 in the pump casing, the latter being provided with a suction valve 11, and a discharge valve 12. The pump preferably has a displacement which is considerably greater than is required to supply the maximum amount of fuel to the engine. This is advantageous because it avoids too great a refinement in the regulation and also because it minimizes the effect of leakage around the piston and past the valves. Fuel is admitted to the supply chamber 13 by the pipe 14 connected with any suitable source, and is discharged to the pipe 15 leading in the present case to a fuel pulverizer, atomizer, or injector 70 opening into the engine cylinder. The suction valve is provided with a depending stem 16 and situated below it is a lifter 17 containing an adjustable screw 18 that engages the lower end of the valve stem for the purpose of raising and holding the suction valve off its seat for variable portions of the plunger strokes. The lifter has a considerably greater movement than is normally required to permit the valve to seat. Since 75 the two are not mechanically united this can readily take place. The valve may be seated by gravity, or it may be seated partly by gravity and partly by a light spring 19.

The lifter is mounted on a spindle 20 which projects through the wall of the chamber 13 and has attached thereto an arm 21. The parts 17, 18 and 21 may for convenience be termed a lifter because, although separate, they move as one element. To the outer end of the arm is connected a rod 22, the upper end of which is provided with a pin 23 arranged to slide in the slot 24 in the lever 25. This lever is provided with a fixed fulcrum 26 carried by any suitable support, 80 85 90 95 100 105 110

such for example as a part of the engine frame 27. Thus it will be seen that the reactions of the lever due to the reversal of the direction of motion of the cross-head are transmitted to the fulcrum and not to the speed governor as heretofore has been the general practice. The right hand end of the lever is provided with a fork that embraces a pivoted block 28, the latter being carried by the cross-head 7 so that as the cross-head moves up and down the lever will be vibrated in synchronism therewith, always having a definite stroke in a definite region. In order to vary the portion of the 10 plunger stroke that the suction valve is held off of its seat by the lifter (in other words the timing of the suction valve), a link 29 is provided which is connected to the rod and also to the lower end of a bell crank lever 30. The upper end of the bell crank lever is connected to the sliding collar 31 of the speed governor 32, the latter being driven by a shaft 33 which may be geared to the main shaft of the engine. As the weights of 15 the governor move in and out due to speed variation the upper end of the rod 22 is moved toward and away from the cross-head so that the point of application of power of the vibrating lever to the rod 22 is changed. That is to say the position of the pin 23 coincides with the point of application of power of the lever to the rod and this pin is moved back and forth in the slot 24 to change the amount of fuel delivered to 20 the engine. The result of this is to change the effective length of the rod 22, said effective length being greatest when the rod is in an upright position and gradually growing less as it is moved to the left. As shown the 25 control of the suction valve is automatic, but if it be desired to control the engine by hand, as is desirable in some cases, the upper end of the rod 22 may be moved back and forth by hand, as for example by means 30 of a link 29, a locking device being provided where necessary.

In Fig. 3 is shown a slight modification wherein 25 indicates the lever which is vibrated by the cross-head and 26 the fixed 35 pivot therefor. 22 indicates the rod which is provided with a head 34 carrying rollers 35 suitably supported on pivots and engaging the top and bottom surfaces of the lever. The head is slotted at 36 so that it can pass 40 over the projecting pivot 26. This arrangement reduces friction and in some cases permits of a shorter lever.

Referring to Fig. 2 which indicates diagrammatically the action of my invention, 45 25 is the constantly vibrating lever and 26 its fixed pivot. 21 indicates the arm for moving the suction valve lifter 17, the latter having been omitted for simplicity since said arm and lifter have the same movements. 11 indicates the suction valve which

is shown as resting on its seat and 16 the stem therefor. 22 indicates the rod which is hinged to the arm 21 at its lower end and is adjustable or movable to and fro on the lever 25. The position of the rod indicates 50 that the supply of fuel to the engine is at or about the minimum. Swinging the upper end of the rod to the right will increase the supply of fuel because the suction valve 11 will be permitted to close at an earlier part 55 of the discharge stroke of the plunger and hence more fuel will be discharged through the valve 12. During the portion of the plunger stroke that the arm 21 is above the position shown the suction valve will be 60 open, and during the portion of the stroke that the arm is below the stem of the valve it will be closed. Moving the upper end of the rod 22 to the left from its upright position has, as before stated, the effect of shortening the connection between the lever 25 and the arm 21. I may accomplish this result by the arrangement shown in Fig. 4 wherein the rod 22 is made in two parts, each of which is provided with a screw 65 threaded end 37, the threads on one part being left handed and those on the other right handed. These threads should have a quick pitch to give a considerable longitudinal movement of the parts of the rod for a 70 small angular movement of the nut 38, the latter being connected by the arm 39 to the link 29 previously referred to. It is also preferable to employ double or triple screw threads to reduce wear. The upper end of 75 the rod will in this case, be pivotally united to the lever 25 instead of sliding thereon.

Fig. 5 shows another arrangement suitable for use where a considerable lengthwise movement of the parts of the rod 22 is desired. The adjacent ends of the rod are provided with rack teeth 40 that mesh with a gear 41 carried by a holder 42 which also guides and holds the parts of the rod in alignment. To the spindle of the gear is attached an arm that is connected to the operating device 29. I have only shown one pump plunger and its valves but it is to be understood that they can be duplicated at will and that all the suction valve lifters 100 will be moved by the rod 22.

From the foregoing it will be seen that the vibrations of the lever 25 do not affect the speed governor and that the only load imposed on said governor is that of moving 105 the upper end of the rod 22 or changing its length to vary its effective action. Inasmuch as the pump is of the reciprocating type, the governor can easily adjust the position of the pin 23 or change the length 110 of the rod when there is no load on it, i. e. at the instant of reversal of the direction of motion of the cross-head at the upper and at the lower ends of its stroke. Another advantage in my construction over the 115

prior art is found in the fact that the work of moving the suction valve and of holding it off of its seat against the pressure of the fluid discharged by the plunger on its working stroke is done by the lever, and hence all the governor has to do is to shift one end of the rod 22 which is easily done as above stated. Practical experience has demonstrated that my improved arrangement is more sensitive than those in which the suction valve is actuated by a vibratory lever whose fulcrum is adjusted by the speed governor.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, 25 is:—

1. In combination, a cylinder, a plunger therefor, suction and discharge valves for the cylinder, a lever that is vibrated in synchronism with the pump plunger, a fixed fulcrum for the lever, a member for varying the portion of the discharge stroke of the plunger that the suction valve is held off of its seat, and connecting means interposed between the lever and member which 30 is adjustable to change the timing of the suction valve.

2. In combination, a cylinder, a plunger therefor, suction and discharge valves for the cylinder, a lever that is vibrated in synchronism with the pump plunger, a fixed fulcrum for the lever, a member for varying the portion of the discharge stroke of the plunger that the suction valve is held off of its seat, a connection between the lever 45 and member, and a speed responsive device for varying the effective action of said lever and connection on the member.

3. In combination, a cylinder, a plunger therefor, suction and discharge valves for the cylinder, a lever that is vibrated in synchronism with the pump plunger, a fixed fulcrum for the lever, a rod acting to hold the suction valve off of its seat for a portion 50 of the discharge stroke of the plunger, said rod being operatively connected to and moved by the lever, and means for changing the effective length of the rod to vary the time of closing of the suction valve.

4. In combination, a cylinder, a plunger 60 therefor, suction and discharge valves for the cylinder, a lever that is vibrated in synchronism with the pump plungers, a fixed fulcrum for the lever, a lifter for the suction valve, a rod connecting the lifter and lever, and means for adjusting one end of

the rod to vary the point of application of power of the lever to said rod.

5. In combination, a cylinder, a plunger therefor, suction and discharge valves for the cylinder, a lever that is vibrated in synchronism with the pump plunger, a fixed fulcrum for the lever, an arm for actuating the suction valve, a rod connecting the arm and the lever, and a speed governor which slides one end of the rod on the lever to 70 vary the application of power of the lever to the rod.

6. A fuel pump for internal combustion engines comprising a cylinder and plunger therefor which displaces on each stroke 80 a considerably greater amount of fuel than is necessary for the maximum load of the engine, suction and discharge valves for the cylinder, a lifter for the suction valve, a vibrating lever, a fixed pivot therefor, a 85 rod to be connected to the lifter at one end and movably connected to the lever at the other, and means for moving the rod along the lever toward or away from said fixed pivot.

7. In combination, a cylinder, a plunger therefor, suction and discharge valves for the cylinder, a lever vibrated in synchronism with the pump plunger, a fixed pivot 95 for the lever, a lifter for the suction valve, a rod connecting the lever and lifter and transmitting movements of the former to the latter, and means for changing the effective action of the rod on the lifter.

8. In combination, a cylinder, a plunger therefor, suction and discharge valves for the cylinder, a means for reciprocating the plunger, a lifter for the suction valve, a member vibrated in synchronism with the pump plunger, a connector between the 100 member and the lifter, and means for moving one end of said connector to change the effective action of the member on the lifter.

9. In combination, a cylinder, a plunger therefor, suction and discharge valves for the cylinder, a means for reciprocating the plunger, a lifter for the suction valve, a member vibrated in synchronism with the pump plunger, a rod which connects the member and the lifter and is pivotally secured to one of them, and means for sliding 115 one end of the rod with respect to its co-operating element to change the effective action of the member on the lifter.

10. In a pump, the combination of a cylinder, suction and discharge valves therefor, a plunger, a lifter for the suction valve, a lever for moving the lifter, a rod that reciprocates in synchronism with the plunger, and transmits motion to the lever, one end 120 of said rod being pivoted, the other end being movable to change the timing of the suction valve, and means for moving the last named end of the rod.

11. In a pump, the combination of a cyl- 130

inder; a plunger, suction and discharge valves therefor, a lifter for the suction valve, a lever for moving the lifter, a member which moves in synchronism with the 5 plunger, a rod which directly connects the lever and member, means pivotally uniting the rod to one of said parts, means slidably connecting the rod to the other of said parts, and means connected to said rod for sliding 10 one of its ends on its coöperating part.

12. In combination, a cylinder, a plunger therefor, suction and discharge valves for the cylinder, a lever that is vibrated in synchronism with the pump plunger and has a 15 constant length of stroke in a fixed region, a fixed fulcrum for the lever, a lifter that is adjustable to vary the portion of the dis-

charge stroke of the plunger during which the suction valve is held off of its seat, a means connecting the lever and the lifter to 20 transmit movements of the lever to the lifter, said means being pivotally secured to one of said parts, and arranged to slide on the other, and a device for adjusting said sliding end when the pump is operating to 25 change the time of closing of the suction valve on each stroke of the plunger.

In witness whereof, I have hereunto set my hand this 7th day of November, 1912.

ALEXANDER F. MACDONALD.
